(57) **CLAIM**

The ornamental design for a cover guard for an electronic component as shown and described.

DESCRIPTION

FIG. 1 is a top perspective view of a cover guard for an electronic component according to the invention.

FIG. 2 is a bottom perspective view of the cover guard of FIG. 1.

FIG. 3 is a top view of the cover guard of FIG. 1.

FIG. 4 is a bottom view of the cover guard of FIG. 1.

FIG. 5 is a front view of the cover guard of FIG. 1.

FIG. 6 is a rear view of the cover guard of FIG. 1.

FIG. 7 is a left side view of the cover guard of FIG. 1.

FIG. 8 is a right side view of the cover guard of FIG. 1.

FIG. 9 is a section view of a bottom perspective view of the cover guard taken along lines 9-9 of FIG. 4 illustrating the contours of a portion of the interior of the cover guard; and, FIG. 10 is a section view of a bottom perspective view of the cover guard taken along lines 10-10 in FIG. 4 illustrating the contours of a portion of the interior of the cover guard.
